UNITED STATES PATENT OFFICE.

AXEL JOHNSON, OF OAKLAND, CALIFORNIA.

OPERATING MEANS FOR CASEMENT WINDOWS.

Application filed February 1, 1922. Serial No. 533,180.

To all whom it may concern:

Be it known that I, AXEL JOHNSON, a citizen of the United States, residing at Oakland, in the county of Alameda and 5 State of California, have invented certain new and useful Improvements in Operating Means for Casement Windows, of which the following is a specification.

This invention relates to an operating and 10 retaining device for reversible casement windows fulcrumed either for vertical or horizontal movement.

The invention consists broadly in providing a device movable in a plane parallel with 15 one end of the window and connected therewith and operated from the exterior of the sash whereby movement of the same in opposite directions will cause a like movement of the window.

20 The invention has for its principal objects to provide a simple construction adapted for attachment and concealing within the sash; to provide a construction equipped with a jam nut, the operation of which will 25 lock the window in its adjusted position; to provide a construction which is adapted for insertion or positioning as a unit at little cost, and which will readily adapt itself for the operation of the common link type of 30 reversible casement windows.

With the above mentioned and other objects in view, the invention consists in the novel construction and combination of parts hereinafter described, illustrated in the 35 accompanying drawings, and set forth in the claims hereto appended, it being understood that various changes in the form, proportion, size and minor details of construction within the scope of the claims may be 40 resorted to without departing from the spirit or sacrificing any of the advantages of the invention.

To more fully comprehend the invention reference is directed to the accompanying 45 drawings, wherein:

Figure 1 is a view in section, taken on line 1—1 of Figure 2, of a reversible casement in its sash illustrating the casement mounting links.

50 Figure 2 is a view in broken front elevation of a casement and its sash illustrating one embodiment of my invention connected therewith.

55 Figure 3 is a sectional view taken on line 3—3 of Figure 2 illustrating one of the casement mounting links, the casement guide

operating chain, the connection between the chain and guide, the arrows indicating the path of movement of the casement when operated.

60 Figure 4 is a view in longitudinal detail section of the casement operating unit taken on line 4—4 of Figure 5.

Figure 5 is a longitudinal sectional view taken on line 5—5 of Figure 4.

65 Figure 6 is a vertical sectional view taken on line 6—6 of Figure 1 viewed in the direction of the arrow with the casement closed.

70 Figure 7 is a vertical sectional view through one of the sprockets and its bearing taken on line 7—7 of Figure 4, and

75 Figure 8 is a view in broken perspective of the bearing plate, guide rail and angle plate.

80 Referring more particularly to the several views of the drawings wherein like characters of reference designate corresponding parts, 1 indicates any conventional form of window sash in which is mounted a reversible casement 2, the present embodiment illustrating what is commonly termed "a horizontally movable casement", although it will be understood that the present invention is equally as well adapted to a vertically 85 movable reversible casement.

85 In the present disclosure, particularly Figure 6, the top wall 3 of the sash is formed with a channel in which is mounted a channel guide 4 into which projects a guide pin 90 or member 5 extending upwardly from one end of the casement 2, Figures 1, 2 and 6 of the drawings. The top and bottom edges of the casement 2 are longitudinally recessed for their full length, as at 6, which

95 recesses open toward the inner face of the casement, and within each of said recesses is mounted a link mounting arm 7 held in place by screws 8, the upper link mounting arm carrying at its terminal end the member 5, and said upper and lower arms at their inner ends each terminate slightly to one side of the vertical center of the casement. Each pivotally connects, as at 9, with one end of a casement mounting

100 link 10, the opposite end of said respective links being pivotally secured as at 11 to fixed plates 12 mounted as illustrated in Figures 1, 3 and 6 of the drawings, at one end of the sash opening. Disposed longitudinally of the sash opening and arranged slightly below the outer edge of the

sill 13 is a bearing plate 14 secured to the upper surface of the outer sill 15, and the inner edge of said bearing plate is raised providing a guide rail 16 extending longitudinally beneath the outer edge of the sill 13 with its downwardly extended vertical portion 17 in contact with the inner edge of the outer sill 15. Connected with the lower edge of the casement 2 at a point beneath the upper guide pin 5 through a vertical fulcrum 18 extending into the member 7 is a casement guide plate 19 carrying spaced fingers 20 overlying the guide rail 16, as in Figures 3 and 6. This construction is the conventional reversible casement construction now universally in use, and my present invention relates to the following designed operating means for moving the casement and for retaining the same in its adjusted position.

Secured to the rough sash 21 disposed beneath the inner sill 13 is an angle plate 22 disposed with its horizontal upper surface 23 in the same plane with the bearing plate 14, and with its vertical wall or flange 24 in close parallel relation with the portion 17 of bearing plate 14. The angle plate 22 is of a length corresponding to the width of the sash opening and the flange 24 thereof, on its inner side, adjacent opposite ends, carries conventional bearing frames 25 and 25', the frame 25' being retained in fixed position by the retaining nuts 26, and the frame 25 being mounted for slight longitudinal movement relatively to the plate, which movement is accomplished by the slotted openings 27 through which extend the bolts 28. Each of the frames rotatably carries a shaft 29, and each shaft carries a sprocket 30, the teeth of which sprockets project upwardly through openings 31 in the upper surface 23 of the angle plate. Around the sprockets and through openings 31 extends a suitable casement operating chain 32, the upper flight of which rests on and moves longitudinally of the upper surface of the angle plate, and has connection at one point through part 33 with the guide fingers 20 of the plate 19. The connection between the guide fingers and chain is so arranged that when the casement is in fully closed position, the upper flight of the chain will rest with said part 33 directly above one of the sprockets 30. An adjustable spring tension member 34 associated with bearing frame 25, Figures 4 and 5, maintains the chain 32 under tension.

The shafts 29 extend outwardly through the rough sash 21 and lower sash trim 35, as in Figure 7, and the polygonal ends of said shafts extend part way through corresponding openings in bearings 36. The bearings 36 are flanged, as at 37, on their inner ends, and are mounted within pockets

or recesses 38 in the sash trim 35. The bearings are rotatably mounted in bearing orifices formed centrally in face plates 39, said plates being secured as by screws 40 to the sash trim and formed with a series of annular serrations or teeth 41 on their outer faces. The outer end of the bearing 36 is threaded, and on the same is adjustably mounted a jam nut 42 preferably circular in formation, and provided with a flange 43 affording a gripping surface. The adjustment of the jam nut on the threaded end of the bearing causes a jamming of the bearing and a retaining of the nut by the serrations 41 whereby the casement is locked in its adjusted position. To rotate either of the shafts to operate the casement a crank shaft 44 may be employed, the polygonal end 45 of which is received in the polygonal opening within the bearing 36.

It will be observed that it is only necessary to insert the end 45 of the crank 44 into one of the openings in the bearings 36 and rotate the bearing after both jam nuts 42 have been released, and the casement will be operated to any desired position, either full open or closed, or if desired completely reversed.

In an installation of the type illustrated, wherein the window is a horizontal swinging casement, both shafts 29 may extend through the sash trim and afford two operating points for the casement, but where a vertical swinging casement is employed, it is only necessary to extend one shaft through the sash trim preferably the lower shaft to place the operating point in convenient reach of one desiring to operate the sash.

It will be observed that in the present window construction a departure is made from the conventional form, which departure consists in positioning the fulcrum points 11 and 18 in offset relation to each other affording the easy operation of the fulcrum 9 connecting members 7 and 10, and which improved construction overcomes the dead centering of the fulcrum 9 when the window is closed, which is the case when fulcrums 11 and 18 are in alignment.

I claim:—

- An operating means for a casement window provided with a guide rail longitudinally of which one edge of the window slides, the same comprising an angle plate for disposing with one face parallel with the guide and co-extensive therewith, and with the outer face in a horizontal plane and provided with sprocket openings, a pair of bearing frames carried on the underside of the plate, a sprocket within each bearing frame and one projecting through each opening, a shaft supporting each sprocket, a chain operating over said sprockets and passing through said sprocket openings, whereby one flight operates over one face

of said plate, a yieldable take-up for said chain, and an operating connection between the chain and casement.

2. In combination with a sash provided with a guide rail, a reversible closure mounted to close the sash opening, a guide part pivotally connected to the closure at one end and co-operating with the rail to cause a movement of said closure end in a straight line within said sash, a link fulcrumed at one

end to the closure at its approximate center and at its opposite end fulcrumed to one end of the sash, said latter fulcrum being offset from the fulcrum connection between the closure and guide part, and an operating member connected with the closure for operating the same. 15

In testimony whereof I have signed my name to this specification.

AXEL JOHNSON.
